CLAIM

The ornamental design for a smoking pipe bowl with cover and cover lever, substantially as shown.

DESCRIPTION

FIG. 1 is a perspective view of a smoking pipe bowl with cover and cover lever, showing my new design; FIG. 2 is a side elevational view, the opposite side being identical thereto; FIG. 3 is a top plan view thereof; FIG. 4 is a front elevational view thereof; FIG. 5 is a rear elevational view thereof; FIG. 6 is a bottom plan view thereof.
